UNITED STATES PATENT OFFICE

REINHOLD A. NORLING, OF AURORA, ILLINOIS, ASSIGNOR TO INDEPENDENT PNEUMATIC TOOL CO., OF CHICAGO, ILLINOIS, A CORPORATION OF DELAWARE

DRILL STEEL RETAINER

Application filed November 28, 1930. Serial No. 498,721.

This invention relates to a drill steel retainer for impact tools and more particularly for portable pneumatic tools of the relatively large pavement or concrete breaker type.

The main object of the invention is to provide a simple yet durable and strong retainer construction as required for tools of the type referred to, and also to provide a retainer which can be conveniently and easily operated by the operator of the tool to release as well as retain the drill steel or other working element in the tool.

Another object of the invention is to provide a retainer in which the operable member for releasing the drill steel from the tool or retaining it in the tool is movably mounted on the exterior of the tool in position always accessible by the operator for movement into or out of drill steel releasing or holding position.

Another object of the invention is to provide means for holding the operable member against accidental movement when in either of its two positions, and to have such means act automatically on the member reaching the limits of its aforesaid positions.

Another object of the invention is to have the holding elements of the retainer housed and concealed by the operable member so that said elements will be protected and not injured on contact of the tool with the work or surrounding objects.

Specifically, the retainer structure of the invention includes a sleeve or cam ring as the operable member rotatably mounted on the exterior of the nozzle of the tool to control the projection of retainer elements in the form of balls into and out of the path of a shoulder in the form of a collar on the portion of the drill steel with the nozzle to either release the drill steel or retain it in the tool. The sleeve or cam ring carries a spring pressed detent cooperating with a groove in the nozzle to limit the extent of turning movement which can be given to the sleeve and also to hold the sleeve from accidental turning when at the limit of either of its two positions.

The invention consists further in the matter hereinafter described and claimed.

In the accompanying drawing—

Fig. 1 is a side view of a pavement breaker equipped with a drill steel retainer of my invention;

Fig. 2 is an enlarged longitudinal sectional view taken through the nozzle of the tool and the retainer;

Figs. 3 and 4 are transverse sectional views taken on lines 3—3 and 4—4, respectively, of Fig. 2; and

Fig. 5 is a view similar to Fig. 4, showing the retainer in release position.

In the drawing, 1 indicates the barrel of the tool, 2 the handle at one end of the barrel, and 3 the nozzle at the other end of the barrel for the drill steel 4 or other working element with which the tool may be equipped. A piston 5 is reciprocated in the barrel 1, as in tools of this character, through the actuation of a valve (not shown) at the handle end of the barrel. An anvil block 6 is located in the nozzle 3 between the piston 5 and drill steel 4, and imparts the blow of the piston on its power stroke to the drill steel. The barrel, nozzle and handle parts of the tool are secured together in alignment by long bolts 7, at the sides of the tool, as shown in Fig. 1.

The drill steel 4 is in the form of a long bar of the desired shape and size and has its inner or upper end portion slidably fitted in the nozzle 3, as shown in Fig. 2. The bore of the nozzle at its outer end is enlarged to accommodate an outwardly extending collar 8 on the drill steel which collar provides a shoulder with which the retainer cooperates to hold the drill steel in the tool.

The retainer of my invention is associated with the nozzle 3 and comprises a number of retainer elements which as shown in the drawing are in the form of balls 9 located in holes 10, 10 in the nozzle in advance of the shoulder or collar 8 on the drill steel. The holes 10 extend through the nozzle so that the balls 9 may project into the same in advance of the shoulder or collar 8 and prevent the drill steel 4 from dropping or being shot out of the nozzle when out of contact with the work. The retainer elements 9 are held in the position referred to by an annular

member 11 in the form of a sleeve or ring rotatably fitted on the outside of the nozzle over the balls. Sleeve 11 has a number of internal recesses or cavities 12, one for each ball 9, so that when the sleeve is turned to position its recesses opposite the balls, the latter may enter the recesses to release the drill steel 4 from the nozzle. The balls 9 will be forced into these recesses by the collar 8 as it passes the balls on withdrawing the drill steel from the tool. To aid in this action, the collar 8 has an inclined outer surface 13 to engage the balls as it is drawn past them. The inner surface portions 14 of the sleeve 11 between the recesses 12 fit against the outer surface of the nozzle 3 and when turned over the outer ends of the holes 10 prevent movement of the balls from the collar 8 and thus retain the drill steel in the nozzle. As shown in Figs. 3 and 4, the retaining balls 9 are arranged in the same general plane and are spaced about the axis of the nozzle so as to project into the path of the collar at a number of points about the same.

To hold the sleeve 11 against accidental turning when in either of its two positions, I provide a detent 15 in the form of a ball, as shown in Figs. 4 and 5. The detent element or ball 15 is carried by the sleeve 11 in a hole 16 therein and extends into a circumferentially extending groove 17 in the outer surface of the nozzle under the sleeve 11. Groove 17 has shallow recesses or notches 18, 18 at its opposite ends to receive the detent ball 15, as shown in Figs. 4 and 5. The detent ball 15 is held in its hole 16 and in the groove 17 by a spring clip 19 which partially encircles the sleeve 11 on the outside thereof in a retaining groove 20, as shown. The clip 19 is held from turning on the sleeve by shoulders 21, 21 against which the ends of the clip engage. In this way, the clip cannot turn on the sleeve 11 to release the detent ball. With the clip extending over the outer portion of the ball, the latter may move outward against the clip 19 as the sleeve 11 is turned to release or lock the drill steel in the nozzle. The length of the groove 17 is such that the sleeve cannot be turned a distance greater than necessary to cover and uncover the holes for the retainer balls. The detent ball 15 being constantly engaged by the clip snaps into the notches 18 as soon as the ends of the groove 17 are reached and stops the turning of the sleeve and also automatically locks the sleeve against accidental movement. The tension of the spring clip 19 is readily overcome on manually turning the sleeve 11. Fig. 4 shows the sleeve 11 turned to a position holding the retaining balls 9 under the collar 8, while Fig. 5 shows the sleeve turned to a position to release the retaining balls from the collar.

The sleeve 11 fits freely on the nozzle 3 and is prevented from moving up on the same by a shoulder 22 on the nozzle at the inner or

upper end of the sleeve. The shoulder provides a solid abutment on the nozzle for the sleeve and holds the sleeve against upward movement on the nozzle due to the inertia of the sleeve by the jars produced through the impacts of the drill steel on the retainer means in the operation of the tool. With the sleeve so held, the detent 15 is not required to hold the sleeve against these jars and thus is not subject to any appreciable wear. The sleeve is prevented from moving off the nozzle in the opposite direction by the detent ball 15 carried by the sleeve extending into the groove 17 in the nozzle. The recesses 12 in the sleeve 11, as shown in the drawing, are curved to accommodate the balls 9, and are made larger than the balls, so that the walls of the recesses when turned against the balls will have a cam action thereon to move them into the bore of the nozzle for drill steel retaining purposes. The clip 19 extends more than halfway around the nozzle and being of the split type and made of spring metal may be readily slipped on and off the nozzle in the assembling and disassembling of the retainer. The ends of the clip are turned outward so as to easily ride over the surface of the nozzle when applying and removing the clip. The shoulders 21 are the ends of the groove 17 and are formed by that portion of the nozzle which is not occupied by the groove.

The space 22^a in which the anvil block 6 has movement is shorter than the distance between the retaining balls 9 and a shoulder 23 at the inner end of the bore of the nozzle in which the collar 8 is located. This arrangement permits the anvil block 6 under a blow of the piston to hit the nozzle before the collar contacts with the retaining balls, thereby relieving the same of any direct impact of the piston. The detent ball 15 is smaller than the retainer balls 9, and is offset to one side of the latter as shown in Fig. 2.

The retainer of my invention is simple, yet strong and durable in construction as required for pavement and concrete breaker type of tools. The turnability of the sleeve 11 into and out of the releasing and holding positions, with the sleeve being stopped when reaching these positions, allows for a convenient and quick locking and unlocking of the retainer device. Moreover, with the active elements 9 and 15 of the retainer completely housed by the sleeve 11, the latter protects the same from injury by contact with the work, as when the tool is laid on the same or dragged over it. The sleeve 11 also protects these parts from contact with surrounding objects as the tool is handled and transported from place to place. Furthermore, the retainer is in keeping with the cylindrical design of the tool and with no parts projecting from the tool, they are not

subject to injury nor do they give an unsightly appearance to the tool.

The details of construction and arrangement of parts shown and described may be variously changed and modified without departing from the spirit and scope of my invention, except as pointed out in the appended claim.

I claim as my invention:

- 10 A drill steel retainer for impact tools, comprising in combination with the nozzle of the tool and drill steel insertable into the nozzle, of means providing a shoulder on the portion of the drill steel within the nozzle, retainer means carried by the nozzle and projectable into the same in advance of said shoulder, a sleeve rotatably mounted on the nozzle for controlling the projectability of the retainer means into the nozzle, a spring 15 pressed detent carried by the sleeve and extending into a circumferential groove in the nozzle to limit the extent of rotation of the sleeve, and a shoulder on the nozzle above the sleeve, said shoulder forming a solid 20 abutment for the sleeve to prevent upward movement of the same on the nozzle due to inertia through the impacts of the drill steel on the retainer means in the operation of the tool.
